PUNCH

Frank Benjamin Graham, Lansing, Mich.

Application July 19, 1943, Serial No. 495,330

1 Claim. (Cl. 164—124)

Broadly stated, the object of this invention is to provide novel means for assembling a punch with a punch retainer, the construction being such that, after the punch is assembled with the retainer the punch can neither rotate about its axis nor move longitudinally, until manipulated by an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in side elevation, a device constructed in accordance with the invention;

Fig. 2 is an end elevation;

Fig. 3 is a plan showing the surface of the block which is entered by the punch;

Fig. 4 is a cross section on the line 4—4 of Fig. 3;

Fig. 5 is a cross section on the line 5—5 of Fig. 3;

Fig. 6 is an elevation showing the punch.

The device forming the subject matter of this application includes a retainer H, preferably but not necessarily of rectangular outline. The retainer H comprises a block-like head I to which a closure plate 2 is applied. The closure plate 2 is held on the block I by diagonally disposed securing elements 3, such as screws. Diagonally disposed dowel pins 4, preferably forming a rectangle with the screws 3, extend through the block I and the plate 2. The projecting dowel pins 4 and the screws 3 form means for locating the retainer on a punch holder (not shown).

The block I has a central guideway 5 which, preferably, is of circular cross section. The block I is supplied with an end bore 6 and with a side bore 7, disposed approximately at right angles to the longitudinal axis of the guideway 5. The bores 6 and 7 are spaced apart circumferentially of the guideway 5, and in a direction parallel to the longitudinal axis of the guideway, the bore 7 being an outer bore, and the bore 6 being an inner bore.

A keeper 8, in the form of a ball, is mounted to rotate in the bore 7 and the constituent ma-

terial of the block I engages the keeper, as shown at 9, to prevent the keeper from leaving the bore 6 when the punch (hereinafter described) is removed, the keeper however, extending a little way into the guideway 5. The keeper 8 is held in place by a screw 10, threaded into the bore 7 and held against outward movement by a plug 11 in the outer end of the bore 7 and preferably made of hard wax. The keeper 8 has no movement longitudinally of the bore 7.

In the bore 6 is mounted a ball latch 12 held, as hereinbefore described, and as shown at 9, in connection with the spherical keeper 8, so that it can project a little distance into the guideway 5, but not roll into the guideway when the punch is removed. A screw abutment 14 is threaded into the bore 6, a compression spring 15 being interposed between the screw abutment and the ball latch 12. The ball latch 12, therefore, has movement longitudinally of the bore 6.

The punch is marked by the numeral 16 and may have an enlarged end portion 17. The enlarged end portion 17 of the punch 16 fits closely, but rotatably and slidably in the guideway 5 of the block I. The part 17 of the punch 16 is supplied with an L-shaped groove 18, including a longitudinal portion 19, and a transverse portion 20, at the inner end of the part 19 of the groove. The enlarged portion 17 of the punch 16 is terminally beveled as shown at 21.

In practical operation, the part 17 of the punch or similar tool 16 is introduced into the guideway 5 of the block I, the longitudinal portion 19 of the groove 18 receiving the keeper or projection 8. As the punch 16 is advanced, the ball latch 12 is forced outwardly by the beveled surface 21 of the punch, against the action of the spring 15. The plate 2 forms a closure for one end of the guideway 5, and by the time that the beveled end 21 of the punch engages the plate, as in Fig. 5, the keeper 8 is in a position to enter the transverse part 20 of the groove 18 in the portion 17 of the punch.

The punch 16 is rotated, and the keeper 8 enters the transverse part 20 of the groove 18. Thus, the punch 16 is held against longitudinal movement. As the punch 16 is rotated, the outwardly-forced ball latch 12 first rolls on the outer surface of the part 17 of the punch 16, and ultimately enters the longitudinal portion 19 of the groove 18, the punch being held against axial rotation.

By a reverse operation, in which the operator overcomes the thrust of the spring 15, the punch 16 can be detached from the retainer H.

What is claimed is:

In a mounting for a punch or similar tool, a retainer having a guideway extended partway therethrough, an outer ball carried by the retainer and held to extend into the guideway, an inner ball carried by the retainer and spring-pressed to extend into the guideway, the outer ball and the inner ball being spaced apart both longitudinally and circumferentially of the guideway, and a tool insertable longitudinally into the guideway, the tool having a superficial groove comprising longitudinal and transverse portions, the outer ball being received in the longitudinal

portion of the groove, when the tool is inserted as aforesaid, and the inner ball then engaging the tool to one side of the longitudinal portion of the groove, the tool abutting against the retainer, at the inner end of the guideway, to align the transverse portion of the groove with the outer ball, the tool thereafter being rotatable with respect to the retainer, to cause the outer ball to enter the transverse portion of the groove, and
5 to cause the inner ball to enter the longitudinal portion of the groove and to engage one side thereof.

FRANK BENJAMIN GRAHAM.
